No. 748,869.

PATENTED JAN. 5, 1904.

H. McG. HULL.

COLLAPSIBLE CARRIAGE.

APPLICATION FILED AUG. 5, 1903.

NO MODEL.

Fig. 5.

UNITED STATES PATENT OFFICE.

HENRIETTA MCGREGOR HULL, OF DETROIT, MICHIGAN.

COLLAPSIBLE CARRIAGE.

SPECIFICATION forming part of Letters Patent No. 748,869, dated January 5, 1904.

Application filed August 5, 1903. Serial No. 168,383. (No model.)

To all whom it may concern:

Be it known that I, HENRIETTA MCGREGOR HULL, a citizen of the United States, residing at Detroit, in the county of Wayne and State 5 of Michigan, have invented a new and Improved Collapsible Carriage, of which the following is a specification.

My invention relates to collapsible carriages; and the objects of my improvement 10 are to provide a carriage that can be easily and cheaply constructed, that can be easily folded together in a compact package and easily set up, and that will be rigid when unfolded for use. I attain these objects by the 15 construction illustrated in the accompanying drawings, in which—

Figure 1 is a side view of the carriage ready for use. Fig. 2 is a front end view of the carriage-frame. Fig. 3 is a side view of the frame 20 when collapsed. Fig. 4 is an end view of the same. Figs. 5 and 6 show a detail of the hammock-support. Fig. 7 is a button to turn the shaft that controls the position of the wheels. Fig. 8 is a detail of the toggle-links that 25 control the position of the wheels. Fig. 9 is an elevation of the lock of the front hammock-support and the handle. Fig. 10 is a view of the same, taken along the line of the arrow in Fig. 3. Fig. 11 is an enlarged view of the 30 pin that controls this lock, and Fig. 12 is a view of the end of one of the links of the same.

Similar reference characters refer to like parts throughout the several views.

The frame of the carriage is composed of 35 the front and rear cross-bars 1, which carry bearings 2 for the side bars 3. The middle brackets 4 and end brackets 5 support the wheels 6, it being understood that there are two middle brackets 4 between each pair of 40 wheels, one on each side of the wheels. To each end of each side bar is attached a crank 7. To the center of each cross-bar is attached the bearing 8, which bearings carry the shaft 9, which shaft has attached to it outside of 45 each bearing a double crank 10, which is connected by the links 11 to the cranks 7 on the side bars. This shaft may be turned by the button 31, secured to either the front or rear end of the shaft outside of the double crank 50 on that end. In Fig. 8 it will be noticed that the outer end of the link 11 is slotted. The throw of the side of the crank 10, to which

this link is attached, is slightly longer than that of the other side to allow for this slot, the object being to delay the swinging of the 55 wheels on one side, so that there will be no interference between the wheels. The toggle at the other end of the carriage is similar. A pin on the crank and another on the bearing prevent the wheels on the side with the 60 slotted link from swinging out farther than at right angles. (See Fig. 8.) The double cranks are permitted a little more than one-half of a revolution, so that the pins will pass beyond the center each time and act as a partial lock. 65

To the bearings 2 are attached brackets 12, having notches 13 and pins 14. The front hammock-support 15 and the handle 16 have metal stirrups 17 at their lower ends slideable 70 on the pins 14, which stirrups are provided with pins adapted to enter the notches 13. Links 18 are secured at one end to these stirrups and are joined in the center by means of the eccentric-pin 19, which pin may be 75 turned, by means of its button, to push apart or pull together the lower ends of the handle or hammock-support, according to the desire to have them held rigid in the position shown in Fig. 1, or loose, so that they may be folded 80 down to the position shown in Fig. 3. Lugs 20 on these brackets position the support and handle for locking.

Bands 21 and 22 support the umbrella-handle, as shown in Fig. 1, permitting the same 85 to be folded against the carriage-handle. The hammock shown is provided with spreaders 23 and 24. The front end of the hammock is secured to the necks of pins 25, while the rear is provided with springs 26, which connect 90 with the pivoted arms 27, supported by the cross-piece 28. This cross-piece has a pin 29 at each end, which may enter any of the notches 30 in the arm 27, so that these arms may be held at the angle desired. 95

To collapse the carriage, the front hammock-support is first released to fall back by pulling the pins out of the notches 13 by turning the pin 19. The handle is then dropped forward in the same manner. Next the button 31 is turned and the wheels fold up, when the now collapsed structure may be carried by one of the side bars. 100

I have shown the cross-piece 28 and the end

and side bars of tubing; but wood may be used instead. It is obvious that many changes may be made in this structure without departing from the scope of my invention.

5. What I claim as my invention, and desire to secure by Letters Patent, is—

1. In a collapsible carriage, the combination of the wheels, axles for said wheels, a frame, rotatable side bars, and brackets whereby the 10 wheels are carried by the side bars.

2. In a collapsible carriage, the combination of the cross-bars, side bars, wheels supported by the side bars, and toggle-links to turn the side bars.

15 3. In a collapsible carriage, the combination of rotatable side bars, depending braces, wheels carried by said braces with their axles below the line of said side bars, and means to turn the side bars.

20 4. In a collapsible carriage, the combination of a frame comprising front and rear cross-bars, bearings carried by said cross-bars, side bars journaled at their ends in said bearings and wheels carried by said side bars.

25 5. In a collapsible carriage, the combination of the frame, bearings secured to the front and rear ends of the frame, side bars extending from the front to the rear bearings and rotatable in the same, wheels carried by the side 30 bars, a carriage-handle secured to one end of the frame, a support secured to the other end of the frame, a hammock attached at one end to said support and at the other end to said handle, and springs forming the connection 35 between the hammock and handle.

40 6. In a collapsible carriage, the combination of a frame comprising front and rear cross-bars, bearings carried by said cross-bars, side bars extending from the front to the rear 45 bearings and rotatable in the same, wheels carried by the side bars, a carriage-handle pivoted to the rear end of the frame, a support pivoted to the front end of the frame, a hammock carried by the support and handle 50 and locking means to secure the handle and support in their elevated position.

7. In a collapsible carriage, the combination of cross-bars having bearings at their ends, side bars revolvable in said bearings, wheels 55 carried by said side bars, cranks on the ends of said side bars, a shaft supported by said cross-bars, and toggle-links carried by said shaft and attached to said cranks so that the turning of the shaft will swing said wheels to 60 collapse said carriage.

8. In a collapsible carriage, the combination of the cross-bars having bearings at their ends, brackets on said bearings, rotatable side bars, wheels carried by said side bars, a 65 hammock, supports for said hammock pivot-

ed on said brackets, and means to lock said supports to said brackets to hold the same in elevated position and to unlock the supports so they may be folded down on the side bars.

9. In a collapsible carriage, the combination 65 of the frame, comprising rotatable side bars, wheels carried by the side bars, hammock-supports pivoted to the frame, a cross-bar on one of the supports, arms pivoted on said cross-bar, means to lock said arms in the desired angular position, springs secured to said arms and a hammock carried by the springs and the other support.

10. In a collapsible carriage, the combination 70 of the cross-bars, bearings at the center of the cross-bars, a shaft carried by said bearings permitted to turn over one-half revolution each way, double cranks on the ends of said shaft having pins at unequal distances from the center, bearings at the ends of said 75 cross-bars, side bars revolvable in said bearings, wheels carried by said side bars, cranks at the ends of said side bars, links connecting the pins of the double cranks to the cranks on the side bars, one end of the links 80 connected to the pins the greater distance from the center of the double cranks being slotted, and means to limit the movement of the side bar adjacent to the slotted links.

11. In a collapsible carriage, the combination 85 of a frame, bearings at the ends of said frame, side bars each journaled in several of said bearings, wheels carried by said side bars, and means to turn the side bars to swing the wheels up under said frame.

12. In a collapsible carriage, the combination 90 of a frame, bearings carried by said frame, side bars rotatable in said bearings and a plurality of wheels carried by each side bar.

13. In a collapsible carriage, the combination 95 of front and rear cross-bars, bearings at the ends of said cross-bars, side bars extending from the front to the rear bearings, a plurality of wheels carried by each side bar, and means to turn the side bars.

14. In a collapsible carriage, the combination 100 of a frame, comprising rotatable side bars and bearings for the same, braces secured to the side bars, axles carried by the braces, wheels mounted on the axles, and means to turn the side bars.

In testimony whereof I have signed my name to this specification in the presence of two subscribing witnesses.

HENRIETTA McGREGOR HULL.
